UNITED STATES PATENT OFFICE

151,798

DESIGN FOR A HOLLOW GLASS BUILDING BLOCK

John H. Sutter, Norcross, Ga., assignor to Owens-Illinois Glass Company, Toledo, Ohio, a corporation of Ohio

Application October 15, 1947, Serial No. 141,923

Term of patent 3½ years

(Cl. D18—2)

To all whom it may concern:

Be it known that I, John H. Sutter, a citizen of the United States, residing at Norcross, in the county of Gwinnett and State of Georgia, have invented a new, original, and ornamental Design for a Hollow Glass Building Block, of which the following is a specification, reference being had to the accompanying drawings, forming a part thereof.

In the drawings:

Fig. 1 is a front elevational view of a hollow glass building block showing my new design;

Fig. 2 is a top plan view thereof; and

Fig. 3 is a fragmentary sectional view at line 3—3 on Fig. 1.

The opposite side of the block is the same as the side shown in Fig. 1.

I claim:

The ornamental design for a hollow glass building block, substantially as shown and described.

JOHN H. SUTTER.
